UNITED STATES PATENT OFFICE.

JAMES N. PIGGOTT, OF PARKERSBURG, WEST VIRGINIA.

DESIGN FOR A FISH-BAIT.

59,770.

Specification for Design.

Patented Nov. 22, 1921.

Application filed June 30, 1921. Serial No. 481,669. Term of patent 7 years.

To all whom it may concern:

Be it known that I, JAMES N. Piggott, a citizen of the United States, residing at Parkersburg, in the county of Wood and State of West Virginia, have invented a new, original, and ornamental Design for a Fish-Bait, of which the following is a specification, reference being had to the accompanying drawing, forming part thereof, and in which—

Figure 1 is a side elevation of a fish bait showing my new design.

Fig. 2 is a top plan view.

Fig. 3 is a front end view.

I claim:

The ornamental design for a fish bait, as shown.

JAMES N. PIGGOTT.
